INDEX MECHANISM

Clarence J. Green, Worcester, Mass., assignor to
 Norton Company, Worcester, Mass., a corpora-
 tion of Massachusetts

Application March 29, 1939, Serial No. 264,795

4 Claims. (Cl. 51—101)

The invention relates to indexing mechanism, particularly for automatic camshaft grinding machines such as disclosed in patent to Belden and Silven No. 2,022,178.

One object of the invention is to permit an automatic camshaft grinding machine such as disclosed in the aforesaid patent to be more quickly set up for grinding different types of product camshafts. Another object of the invention is to provide a dog bar having a plurality of series of actuating dogs and arranged so that any one of the series can be brought opposite the member to be actuated. Another object of the invention is to provide a series of patterns for controlling the indexing of a master cam roller with respect to the master cams in a camshaft grinding machine. Another object of the invention is to improve the apparatus disclosed in Silven patent No. 1,791,479. Other objects will be in part obvious or in part pointed out hereinafter.

The invention accordingly consists in the features of construction, combinations of elements, and arrangements of parts as will be exemplified in the structure to be hereinafter described, and the scope of the application of which will be indicated in the following claims.

In the accompanying drawing illustrating one of many possible embodiments of the mechanical features of this invention,

Figure 1 is a perspective view of a camshaft grinder having the indexing mechanism of the present invention applied thereto;

Figure 2 is a view, partly in axial sectional view and partly in elevation, of the dog bar which is particularly a subject of the present invention, the center part of the dog bar being broken away;

Figure 3 is a sectional view taken on the line 3—3 of Figure 2;

Figure 4 is a sectional view taken on the line 4—4 of Figure 2;

Figure 5 is an isometric view of the dog bar. In the grinding of cylindrical shafting it is sufficient to rotate the shaft on centers and bring into contact with it a rotating and (relatively) transversing grinding wheel. In order to grind camshafts, some means had to be provided to move the grinding wheel or work piece, one relative to the other, to generate the desired cam contour. In a line of machines exemplified by the patents hereinabove referred to, the grinding wheel was mounted on a cross slide while the work piece was carried by the table or carriage capable of a longitudinal move-

ment. The work piece instead of being in a fixed position on the table or carriage was mounted in centers provided in a rock bar. The table was moved from one position to another to bring successive individual cams opposite the grinding wheel. A series of master cams were provided to rock the rock bar and a master cam roller was movable to a position opposite a particular master cam corresponding to the product cam to be generated.

The design of the product camshaft being determined by automotive engineering, it happened that the distance axially between successive individual cams was not uniform. In the patent to Silven No. 1,791,479 referred to, the motion of the carriage was used automatically to bring the master cam roller opposite the desired master cam, the master cams being uniformly spaced. The apparatus of the present invention is shown embodied in a machine of this type.

Referring now to Figure 1, the machine base is indicated at 10 and on the upper surface thereof are formed V ways 11 and a flat way 12 for the support of a carriage 13 having complementary V ways 14 and a flat way 15. This carriage 13 is, therefore, movable along the base 10 and automatic hydraulic mechanism to move it is disclosed in the aforesaid patent to Belden and Silven No. 2,022,178 while automatic mechanical mechanism to move it is disclosed in patent to Belden and Trefethen No. 1,945,588, and so far as the present invention is concerned the carriage 13 might be manually moved to the various positions desired.

Mounted on and affixed to the carriage 13 is a table 16, normally extending parallel to it but capable of slight angular adjustment, if desired. Mounted upon the table 16 in a bearing 18 and another bearing not shown is a rock bar 20. Fastened to the rock bar 20 is an adjustable tail center 21. The work piece or product cam-shaft W extends between the adjustable tail center 21 and the head center formed on the end of a master cam spindle 23 supporting a plurality of master cams 24. Fastened to the table 16 is a casting comprising a pair of bracket portions 25 and a connecting web 26, which casting supports a slideway 27 for a rack 28. Extending between the bracket portions 25 is a rod 30. Revolvably mounted on the rod 30 is a master cam roller 31. A fork 32 straddles the master cam roller 31 and is connected to the rack 28. Meshing with the rack 28 is a pinion gear 33 mounted on a stud projecting from one

of the brackets 25. Connected to the pinion gear 33 is a small spur gear 35 which meshes with a somewhat larger spur gear 36 mounted on a stud 37 projecting from a lower portion 38 of the casting including the brackets 25. Meshing with the gear 37 is another spur gear 40 mounted on a stud 41 projecting from a boss 42 also constituting part of the casting including brackets 25 and the portion 38. On the end 10 of the stud 41 is a star wheel 43. The star wheel 43 is a rotatable member and it is in effect a detent for actuating the rack 28 in a step by step movement responsive to contact with the dogs to be hereinafter described.

15 The master cam spindle 23 is journaled in the rock bar 20 and as the master cam spindle 23 revolves, the particular master cam 24 in contact with the roller 31 causes the rock bar 20 to oscillate on the table 16. Thus a product 20 cam will be formed of a shape controlled by a master cam 24.

Any suitable means is provided to drive the product shaft W. For example, a motor, not shown, drives a worm 45 in a casing 46 on top 25 of a bracket 47 mounted on the table 16, and the worm meshes with a worm wheel 48 in a casing 49 connected to the bracket 47, the spur gear 48 being connected by a shaft 50 with a spur gear 51 meshing with a spur gear 52 connected to a sprocket gear 53 which is connected by a chain 54 to a sprocket gear 55 on the end of a shaft 56, some of these parts being mounted in the casing 57 as indicated. The shaft 56 is connected by a flexible coupling 59 to the master cam shaft 23. Any suitable means involving a hydraulic cylinder 65 may be used to rock the master cam shaft 23 away from the master cam roller 31 to permit indexing and this same motion will also move the product shaft W away from the grinding wheel 66.

The foregoing is more fully described in the patents hereinbefore referred to and, therefore, will not be further detailed herein. Referring now to all the figures, I provide a dog bar which 45 may consist of an end piece 71 and an end piece 72 mounted in journals 73 and 74 in brackets 75 and 76 fastened to the machine base 10. Each end piece 71 and 72 has a portion which is square in cross section. The end piece 71 is rotatable to four different positions by means of a hand wheel 78 and may be held in any of these positions by means of a spring pressed plunger 79 operated by a handle 80 which enters any one of four holes 81 in the bracket 75.

I further provide four removable dog bar sections 82 each comprising two bars rectangular in cross section and, as shown in Figure 5, spaced apart by blocks 83, the pair of bars being suitably fastened to the blocks and there being blocks 83 at each end of the bars. Each assembly of the dog bar section 82 including the blocks 83 is fastened by means of screws 85 to portions of the end pieces 71 and 72, respectively, which are square in cross section, and I may provide triangular prism blocks 86 fastened to the end pieces 71 and 72 securely to lock the dog bar portions 82 in place.

I provide dogs 90 having enlarged bases 91 and shanks 92 extending through the slots 93 formed between the bars comprising the dog bar sections 82 and secured in place by screws 94 and washers 95 located inside the dog bar. These dogs 90 operate on the star wheel to move the master cam roller 31 whenever the table 16 is moved longitudinally, and the dogs 90 can be spaced

apart as desired on the dog bar. Furthermore, there may be four different arrangements of dogs 90 on the dog bar, one at each side thereof. The dog bar sections 82 can readily be removed by removing a pair of triangular prisms 86, one at each end of the dog bar, and a pair of screws 85 from the blocks 83. The machine may be made ready to grind different types of camshafts W simply by indexing the dog bar so far as the automatic positioning of the master cam roller 10 31 is concerned.

Referring now to Figure 1, it is impossible for the dog bar to be indexed excepting when a cylindrical portion 96 of the end piece 71 is under the star wheel 43. This is because in the 15 turning of the dog bar, the prismatic shape thereof interferes with the stud 41 upon which the star wheel 43 is mounted. It should be understood that by making the dogs 90 longer, the dog bar would be turnable whatever the relative 20 position of the star wheel, assuming no other parts interfere, but I prefer to have this interlock so that the operator is required to move the table to the extreme left-hand position (as he stands in front of the machine), that is to the 25 right in Figure 1, before he can index the dog bar. Otherwise if the dog bar were turned at a point where there were more dogs on one side of the star wheel in the case of one bar than in the case of the other, the machine would be 30 thrown out of timing.

It will thus be seen that there has been provided by this invention an apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth 40 or shown in the accompanying drawing is to be interpreted as illustrative and not in a limiting sense.

I claim:

1. In a camshaft grinding machine, the combination with a grinding table, a rock bar mounted thereon, a master camshaft mounted on the rock bar, a master cam roller for contact severally with the master cams, and mechanism including a star wheel to move the master cam roller to different cams responsive to movement of the grinding table, of a plurality of dog bar sections parallel to each other and united and journaled in the machine whereby any dog bar section may be brought opposite the star wheel 55 to actuate it.

2. In a camshaft grinding machine, the combination with a grinding table, a rock bar mounted thereon, a master camshaft mounted on the rock bar, a master cam roller for contact severally with the master cams, and mechanism including a star wheel to move the master cam roller to different cams responsive to movement of the grinding table, of a plurality of rows of dogs and means for bringing any one row under the 65 star wheel to actuate it.

3. In apparatus of the class described, the combination with a plurality of master cams, an abutment, mechanism for moving one of the foregoing relative to the other to place the abutment selectively opposite different master cams, said mechanism including a rotatable member adapted to be actuated by dogs, of a plurality of sets of dogs and mounting means for the dogs 70 75

permitting any one set to be brought opposite the rotatable member.

4. In apparatus of the class described, the combination with a plurality of master cams, an abutment, and mechanism for moving one of the foregoing relative to the other to place the abut-

ment selectively opposite different master cams, said mechanism including a detent adapted to be actuated by dogs, of a plurality of sets of dogs and mounting means for the dogs permitting any one set to be brought opposite the detent. 5.

CLARENCE J. GREEN.
